(57) **CLAIM**

The ornamental design for a drinking cup, as shown and described.

DESCRIPTION

FIG. 1 is a top perspective view of a drinking cup design showing my new design;

FIG. 2 is a bottom perspective view of a drinking cup design showing my new design;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is a perspective view of FIG. 1 in an open state. Any shading and cross-hatching are not surface ornamentation but are utilized to illustrate the surface contours of the drinking cup design in the drawings.

1 Claim, 9 Drawing Sheets
